UNITED STATES PATENT OFFICE.

ADOLF WILHELM KÜTZER, OF STÜNZ, NEAR LEIPSIC, GERMANY.

ROPE-GRIP FOR SUSPENDED ROPE RAILWAYS.

No. 821,174.

Specification of Letters Patent.

Patented May 22, 1906.

Application filed January 2, 1906. Serial No. 294,326.

To all whom it may concern:

Be it known that I, ADOLF WILHELM KÜTZER, a subject of the Emperor of Austria-Hungary, residing at 20° Hauptstrasse, Stünz, near Leipsic, Germany, have invented certain new and useful Improvements in Rope-Grips for Suspended Rope Railways; and I do hereby declare the following to be a full, clear, and exact description of the invention, such as will enable others skilled in the art to which it appertains to make and use the same.

This invention relates to a rope-grip for suspended rope railways wherein a hauling-rope is clamped between gripping-jaws actuated by the weight of the vehicle and its load, and comprises a traveling frame and rollers, a rope-clamp supported on the frame, rocking shafts passing through the axles on which the rollers are mounted, arms fixed on the shafts at opposite sides of the rollers, a load-hanger suspended from the free ends of a pair of arms on one side of the frame, and gripping-jaws connected with a pair of arms on the other side of the frame.

The advantage of the present rope-grip over others of a similar kind consists in the load being suspended from a point midway of the length of the traveling frame and the strain on the grip being unaltered, or only appreciably so, when the truck moves along an incline. Moreover, all movable parts are easily accessible, so that any damage can be repaired at once from outside.

In the accompanying drawings, Figure 1 is a side elevation of the traveling frame or trolley; Fig. 2, a similar view to Fig. 1 of the opposite side, and Fig. 3 a transverse section.

The load-hanger *a* is suspended from the shaft *b* and cross-head *d*, connected with the levers *k* by means of the slots *g* and bolts *h*.

In the form of the invention illustrated by way of example the shafts *m*, with which the levers *k* are connected, are carried through the axles of the wheels *n*. At the opposite ends of the shafts *m* are short levers *k'*, which are connected with one another by a cross-head *d'*, Fig. 2, bolts *h'*, and slots *g'* after the same manner as the levers *k*. The cross-head *d'* is guided on the lug *p* of the traveling frame by a pin *o*. The two gripping-jaws *q* are pivoted at *r* on brackets on the framing, and arms *q'* on the jaws are connected with the cross-head *d'* by means of the rods *t*. Thus through the weight of the load-hanger and load the cross-head *d*, Fig. 1, is pulled down and therewith also the levers *k k'*, which

pull down the cross-head *d'*. The gripping-jaws *q q'* move correspondingly around their pivots *r* and clamp the trolley firmly to the traction-rope *s*. The invention may, however, be so carried out that only one gripping-jaw is movable, while the other is fixed; but, having regard to the gripping stroke or action, it is desirable that both jaws should be movable. According to the proportional lengths of the levers *k k'* the clamping pressure may be made greater or less. If the ends of the levers *k k'* be provided with toothed segments, the cross-heads *d d'* will not be required.

The space, Fig. 3, left in the central part of the traveling frame may be advantageously employed for receiving a lubricating device by means of which the traveling rope may be furnished with the requisite lubricating material. For the purpose of releasing the trolley the shaft *b* is provided with a roller *u*, which runs in the usual manner on a track inside the station, and thereby causes the levers *k* to swing up, and thus effects the opening of the grip *q*.

What I claim, and desire to secure by Letters Patent, is—

1. In a rope-grip for suspended rope railways, the combination with a traveling frame and rollers and a rope-clamp supported thereby, of rocking shafts, arms on the shafts adapted to operate the rope-clamp, and means for actuating the shafts to which the load is directly connected.

2. In a rope-grip for suspended rope railways the combination with a traveling frame and rollers and a rope-clamp supported thereby, of rocking shafts, two opposite pairs of arms on the shafts, a cross-head arranged to connect one pair of opposite arms, means for connecting said cross-head to the gripping-jaws, and a cross-head connected with the other pair of arms and from which the load is directly suspended.

3. In a rope-grip for suspended rope railways the combination with a traveling frame and rollers and a rope-clamp supported thereby, of rocking shafts, two opposite pairs of arms on the shafts, a cross-head arranged to connect one pair of opposite arms, means for connecting said cross-head to the gripping-jaws and a cross-head connected with the other pair of arms, a hanger to which the load is attached, and a direct connection between the hanger and the last-named cross-head.

4. In a rope-grip for suspended rope railways the combination with a traveling frame

and rollers and a rope-clamp supported thereby, of rocking shafts, two opposite pairs of arms on the shafts, a cross-head arranged to connect one pair of opposite arms, a guide on the frame for said cross-head, means for connecting said cross-head to the gripping-jaws, and a cross-head connected with the other pair of arms and from which the load is directly suspended.

10 5.. In a rope-grip for suspended rope railways the combination with a traveling frame and rollers and a rope-clamp supported thereby, of rocking shafts, two opposite pairs of

arms on the shafts, a cross-head arranged to connect one pair of opposite arms, a guide on the frame for said cross-head, rods to connect the cross-head and gripping-jaws, and a cross-head connected with the other pair of arms and from which the load is directly suspended. 15

In testimony whereof I have affixed my 20 signature in presence of two witnesses.

ADOLF WILHELM KÜTZER.

Witnesses:

HERM TACK,
RUDOLPH FRICKER.

It is hereby certified that the name of the patentee in Letters Patent No. 821,174, granted May 22, 1906, for an improvement in "Rope-Grips for Suspended Rope Railways," was erroneously written and printed "Adolf Wilhelm Kützer," whereas said name should have been written and printed *Adolf Wilhelm Kutzer*, and the names of the witnesses should be *Herm. Sack* and *Rudolph Fricke* instead of "Herm. Tack" and "Rudolph Fricker"; and that the said Letters Patent should be read with these corrections therein that the same may conform to the record of the case in the Patent Office.

Signed and sealed this 24th day of July, A. D., 1906.

[SEAL.]

F. I. ALLEN,
Commissioner of Patents.
